AEROPLANE

Maurice Quemin, Le Mans, France

Application February 16, 1932, Serial No. 593,216,
and in France February 18, 1931

3 Claims. (Cl. 244—12)

The present invention has for its object improvements in aeroplanes, and more particularly that of ensuring the maintenance of the stability of the machine when the pilot reduces speed with a view to landing.

It is known that there is often produced during this manoeuvre a longitudinal or transverse swaying of the aeroplane which may cause some trouble to the pilot, and that numerous accidents for this reason are due to what is usually referred to in aviation terms as "loss of speed".

According to the present invention, in order to permit the pilot to reduce the speed of his aeroplane whilst maintaining its stability, the main wing (or each main wing) of the machine is provided with a small auxiliary wing which receives from below air deflected from the front edge of the main wing which is suitably shaped or disposed for this purpose.

20 A supplementary sustaining effect results from the action of this rising air on the small auxiliary wing, which ensures the maintenance of the stability of the aeroplane when the pilot reduces speed.

25 In the drawing attached hereto, various forms of carrying out the invention are represented diagrammatically by way of example.

In the drawing Figure 1 is a part transverse section of the main wing of a monoplane; Figure 2 is a plan of the monoplane; Figures 3 and 4 are modifications of the front of this wing.

A is the main wing of an aeroplane of known construction.

The front of this wing has a concave shape at 35 B, so that the air which strikes this concave portion is deflected against a small auxiliary supporting surface C mounted above the wing A from which it is carried by uprights C'. This rising air impinging on the surface C, increases the "lift" 40 of the machine.

The surface C can be fixed or may be adjustable in height; it can normally be positioned on the main wing A or mounted in a recess suitably formed in the upper portion of this wing, and is so arranged that it only rises to its operative position and to the height desired when the pilot reduces the speed of his aeroplane. In order to effect this, a toothed pinion (1) and rack (2) 50 may be employed to effect this movement of the

wing C. Any other control may obviously be employed.

In place of forming the front of the main wing A with a concave shape B, as in Figure 1, it can be provided with a movable portion D (Figure 3) 55 which normally provides the usual convex shape of the front of aeroplane wings, and which can be made to pivot about 3, for example, so as to give the front of the wing a concave shape which will ensure the desired deflection of air against 60 the auxiliary surface C.

Instead of providing this deflection of air in an upward direction by means of the concave surface, a screen or deflector E (Figure 4) can be provided at the front of the wing which may 65 be plane or curved, and preferably movable.

The auxiliary wing C will be located as is found necessary more or less forward or backward with reference to the principal wing A, and can have either zero angle of incidence with respect to the horizontal, or such an angle as may be found most efficient; the angle of incidence may even be greater than the angle of incidence of the main wing if necessary. The breadth and length of this auxiliary wing will, of course, be that found 70 most desirable.

It is to be noted that this small auxiliary wing placed above the main wing to receive an ascending current of air deflected from the front of the main wing, with the object of increasing the 80 stability of the aeroplane, is not in any way comparable with the small auxiliary wings which are placed forward of and level with the front part of the main wing on certain aeroplanes and have an angle of incidence less than that of the latter, 85 with the object solely of suppressing what is called "bubbling."

In the case where the aeroplane, instead of being a monoplane, is a biplane or a triplane, each of the main wings can be provided with a 90 small auxiliary wing similar to the small wing C, it being necessary to shape or dispose conveniently the front extremity of each one of these main wings so that they can deflect gusts of air on the small auxiliary wings.

What I claim is:—

1. In an aeroplane, the combination of a main supporting surface having at its front portion a movable deflector plate which normally lies in an inoperative position, means for moving the 100

deflector plate to a position in which it deflects the air upwardly and a small auxiliary supporting surface which is so located at the front of and above the main supporting surface that its underside is subjected to the action of the upwardly deflected air.

2. In an aeroplane wing, the combination of a pivotal deflecting plate provided at the front edge of the wing, with a small auxiliary supporting surface located above and slightly behind said deflecting plate, such that the underside of said small auxiliary supporting surface is sub-

jected to the action of the air deflected by the said deflecting plate.

3. In an aeroplane wing, the combination of a pivotal deflecting plate provided at the front part of said wing, with a small movable auxiliary supporting surface located above and slightly behind said deflecting plate such that the underside of said small movable auxiliary supporting surface is subjected to the action of the air deflected by said deflecting plate.
